UNITED STATES PATENT OFFICE.

ROSS C. CAMPBELL, OF SPRINGFIELD, ILLINOIS.

AWNNG BRACKET.

Application filed September 8, 1926. Serial No. 134,286.

My invention relates to window awnings and more particularly to a class of awnings which may be raised or lowered by a pull cord from within the house, or other structure.

An object of my invention is to provide an awning bracket with window awning fixtures of simple and inexpensive construction which may be readily applied with a minimum amount of labor and having no removable parts to take down and put in storage, and when not in use may be rolled neatly to the top of the window and provide ample ventilation and shade when in use.

15 A further object of my invention is to provide simple and substantial means for holding the awning in lowered position, such means having associated therewith other means whereby in the combination, the awning may be released for raising by first lowering it slightly into a predetermined position to release the locking bar and then releasing a pull cord causing the locking bar to pivotally rotate a bridge member closing 20 the end of the hook member and slidably releasing the locking bar for free upward movement.

25 A further object of my invention is to provide an awning bracket in a window awning fixture adapted to rigidly hold the awning in a lowered position against jerking and shaking about due to the action of strong winds; whereas most awning fixtures are noisy with the wind flopping the fabric—this bracket is adapted to silence all rattling by more firmly binding the locking bar.

30 I attain the objects of my invention in the device described in the annexed specification, recited in the claims and illustrated in the accompanying drawings in which like reference numerals indicate like parts in the several figures.

In the drawings:

35 Figure 1 is a perspective looking down upon the awning bracket of my invention shown in its downward position.

40 Figure 2 is a perspective of my device showing the same in its pivotally upturned position.

45 Figure 3 is a side elevation of the awning bracket of my invention shown in its downward position when in normal use and also tracing in connection therewith a detail of

the movements of the awning locking bar 55 from the time it strikes the bracket of my invention where it slidably moves into locked position, then slidably moves down over the bridge member to engage the same and lift it pivotally up to bridge the hook member and thus release the locking bar for upward free movement.

50 Figure 4 is a perspective of a window awning mounted on a window showing the bracket of my invention when in normal use.

55 Figure 5 is a detail of the stationary or hook member of the awning bracket of my invention.

60 Figure 6 is a side elevation of a window casing showing mounted thereon the awning bracket of my invention.

65 Figure 7 is a front elevation of a window casing showing mounted thereon a window awning showing the window bracket of my invention in use in connection therewith.

70 The awning bracket of my invention is adapted to be used with an awning mounted on a roller —1— at the top of the window casing (see Figures 4, 6 or 7) and in this type of window awning the body member —2— of the awning is secured at the lower end thereof to a U-shaped extension frame member —3— which is adjustably secured at its open ends to the awning brackets of my invention, which brackets are mounted 75 in pairs disposed on opposite sides of the window frame. The body member —2— of the awning is provided with a central horizontally disposed locking bar —4— adapted to detachably engage the awning bracket of 80 my invention when the awning is normally resting in its lowered position.

85 For the sake of convenience in pointing out the merits of the awning bracket of my invention, those who are acquainted with the manufacture and operation of window awnings will understand that roller —19— on which awning body member —2— is mounted and rolled when not pulled down over the window should be of substantial construction with a good strong spring and mounted at the upper end of the window on brackets —20— and —20'—.

90 Locking bar —4— is adapted to be horizontally disposed across the body —2— of the awning and neatly and substantially sewed into a pocket or sleeve running horizontally across the awning body —2—.

While at the same time body member —2— at the lower end thereof is normally adapted to engage U-shaped frame member —3— in a pocket so as to make loose connection 5 thereon.

In order to successfully control a window awning from the inside of the house when using the bracket of my invention, it is advisable to provide a pull cord —21— attached to locking bar —4— centrally of the horizontal portion thereof and to run the pull cord —21— through a pulley of a suitable type —22— and tie it to a hook member of suitable design —23— in suitable position for convenience on the inside of a window.

Referring in detail to the several cooperative parts of the window awning bracket of my invention, I provide a stationary bracket 20 —5— shown in detail in Figure 5, provided with a hook member comprising a stop member —16—, an arm —6— and a slide surface —15—. The hook member is also provided with an aperture —7— adapted to provide 25 pivotal support for the movable member of the window awning bracket of my invention.

Cooperating with stationary bracket —5— is the movable member of the bracket of my invention consisting of an arm member 30 —9— and an integral arm member —10— having a common slot —24— and mounted on stationary bracket —5— through hole —7— and pivotally supported by a pin —8— passing through the stationary and 35 movable members.

The stationary member of my awning bracket is further provided with a lower terminal —12— having a socket —27— therein for the engagement and adjustable support of U-shaped frame member —3— while a thumb screw —26— adapted to hold frame member —3— in its positions of slidable adjustment therein, while integral with arm member —10— is a rib —11— pivotally supporting a bridge member —14— mounted on pin —28— and made long enough to pivotally bridge the space between pin —28— and the lower end of arm —9—. Arms —9— and —10— are integral and in detail 40 of their design they provide a stop member —13— cooperating with stop member —16— on stationary member —5— while arm —10— is formed at point —17— to provide a bumper surface to make contact with surface —18— of stationary member —5— when the awning bracket of my invention is in its lowered position. A point —25— is indicated on bridge member —14— to show the position in which locking bar —4— 45 would normally lift bridge member —14— when the bracket of my invention is being used in normal operation as will now be described.

When the window awning is rolled up and 50 not in use the bracket of my invention is

pivotal turned up in a manner illustrated in dotted lines in Figure 6, and illustrated in larger detail in Figure 2.

When it is desired to lower the awning, the operator will pull up on cord —21— 70 which runs through pulley —22— causing the awning to be lowered by pulling down on locking bar —4— and while the operator is pulling down on locking bar —4—, U-shaped frame member —3— being attached to arm —10— of the movable part of my awning bracket will pivotally lower itself through its own weight as the operator pulls on cord —21— on the inside of the window.

The locking bar will strike the top surface of arm —9— of the movable part, at the same time that it strikes the top surface —15— of the stationary part of my bracket and when it makes this contact, it will be forced to slide down the top surface of arm —9— until it slips off of the lower end of arm —9— at which time, the operator upon slightly releasing his pull on cord —21— permits spring —19— to pull up on locking bar —4— sufficiently strong to slidably move this locking bar up into the hook portion provided in the bracket of my invention by stop member —13— of the movable arm cooperating with stop member —16— of the stationary arm, thereof in which position, it will be found that locking bar —4— will thus substantially bind the movable and stationary members, so that my movable bracket may not be pivotally moved upward about stationary member —5— for the reason that locking bar —4— in this position extends across slot —24— and prevents arm —6— of stationary member —5— from being accommodated through slot —24—.

This arrangement provides a substantial means of holding the awning down successfully against the whip and jerking action of the wind blowing against the awning when it is down, removing in this case any tendency on the part of the moving arm of my bracket to move upward and causes locking bar —4— to become gripped tighter between the recess between the arm —9— and arm —10— of the moving part and the arm —6— of the stationary member —5— of my bracket.

When locked in this position, locking arm —4— thus holds the awning substantially as is shown in Figure 4.

One of the difficulties that has previously been encountered in the attempt to operate window awnings from the inside of the house has been in the matter of automatically locking and releasing the locking bar —4— and since I have just pointed out the novel means of locking the locking bar —4— within the bracket of my invention, I shall now point out the manner of successfully and automatically releasing locking bar —4— when it is desired to raise the awning. 130

The operator will again pull on cord 21 causing locking bar 4 to slidably move down along the top face of rib 11 and bridge member 14 and this locking bar will continue to move downward along this face until it slips off of the lower end of bridge member 14 where, because of the downward pull on cord 21 against locking bar 4 the end of the bar will slip 10 in under bridge member 14 and strike bridge member 14 at point 25; whereupon the operator will slightly release his hold on cord 21 permitting the same to slide through his hand as locking bar 15 4, through the action of spring 19, automatically lifts bridge member 14 pivotally about pin 28 until bridge member 14 makes contact with the lower end of arm 9 permitting locking bar 4 20 to slide easily and quickly off of the bridge member 14 over the top of arm member 9 and on up toward the roller 19 which automatically pulls up on the awning body member 2 until it has rolled 25 the awning up to a point where U-shaped frame member 3 is held substantially against the window frame in the frame member's inverted position in which position the horizontal cross member of the U-shaped 30 frame rests just beneath roller 19.

It will be seen in the drawings in Figure 7, that whereas it is necessary to use the window awning bracket of my invention in pairs positioned on opposite sides of a window frame, it is necessary to mark corresponding parts of the bracket and other fixtures with corresponding numbers where duplication is shown by numbering a part, for instance, number 10 on one side and 40 number 10' on the opposite side.

In explaining the matter of operating the awning bracket we will start for instance with the awning shade rolled up and the U-shaped extension arm member pivotally supported in an upright position and resting with its cross bar near the roller 19 as is shown in the dotted line in Figure 6.

When the operator wishes to pull down the awning to shade the window he or she usually stands inside the window and after 50 releasing cord 21 from anchor 23 a pull up on cord 21 moving through pulley 22 will pull down on locking bar 4 which is secured within a sleeve horizontally disposed across awning body member 2 so as to permit each end of locking bar 4 to extend beyond the edge of the awning to provide locking means for each 55 end of locking bar 4 which ends are 60 designated, one as 4 and the other 4'.

As the operator thus pulls on cord 21 locking bar 4 is pulled down to make sliding contact with the top surface of arm 9 and 9' where locking bar ends 65 4 and 4' are slidably pulled down

along the top surface of arms 9 until locking bar 4 and 4' slip off of the lower ends of 9 and 9' at which time the operator slightly releases the tension of cord 21 and permits locking bar 70 4 and 4' to be quickly pulled up snugly into recesses 13 and 13' through the automatic winding action of spring roller 19 mounted on brackets 75 20 and 20'. While locking bar ends 75 4 and 4' are being held by the spring roller tension into locked position, said locking bar ends are also making contact with stationary hook member 5 at point 80 16 and it will be seen by observing the construction of stationary and movable members of my bracket that due to the fact that stationary arm 6 of stationary member 5 relatively moves through slot 24 of integral bracket member 9 and 85 10, the tendency will be for the movable members of my bracket to substantially bind and hold locking bar ends 4 and 4' up into firm contact with points 13 and 13' and in the meantime against points 90 16 and 16' of the stationary bracket, thus preventing wind from shaking and jerking and lifting the awning when the same is in normal use providing shade for a 95 window.

Movable member 10 being pivotally mounted on a pin extending through aperture 7 in stationary member 5 will pivotally be lowered while locking bar 4 is being pulled down for the reason that 100 U-shaped frame member 3 being attached to the movable member of my bracket at terminals 12 and 12' within sockets 27 and 27' where it is slidably attached and detachably secured by set 105 screws 26 and 26' will thus be lowered by its own weight until bumpers 17 and 17' of movable members 10 and 10' bumps against stop members 18 and 18' of stationary 110 brackets 5 and 5'.

When the operator releases locking bar ends 4 and 4' from engagement with stop members 13 and 13' cooperating with stop members 16 and 16' he effects this release as follows: Pulling on cord 21 again he slidably moves locking bar ends 4 and 4' downward along the top surface of ribs 11 and 11' and down over the top 115 surface of bridge member 14 and 14' until locking bar ends 4 and 4' slip over the lower end of bridge member 14 and 14' and quickly engage bridge members 14 and 14' against the bottom 120 surface at points 25 and 25' where locking bar ends 4 and 4' will quickly lift up on bridge members 14 and 14' and pivotally move bridge members 14 and 14' into position to bridge 125 130

and block the opening between pin —28— and —28'— and the lower points of arms —9— and —9'— of movable members —10— and —10'— of my awning bracket, in which 5 position locking bar ends —4— and —4'— will be quickly released over the end of arms —9— and —9'— and rolled up with awning body member —2— through the automatic control of spring roller —19— when 10 the operator releases slowly the tension which he is holding on cord —21—, thus resulting in pivotally lifting extension arm member —3— as it rolls up the awning and continues to do so until the extension arm 15 member —3— is again at rest in an upright position against the window frame under the roller as is shown in Figure 6 in dotted lines.

To those skilled in the art to which awning brackets pertain, it will be evident that certain minor details of construction may be changed without departing from the spirit and scope of my invention, but the preferred arrangement has been herein above 25 described and is illustrated in the drawings.

Having thus described the nature of my invention, what I claim is:

1. In an awning bracket of the character described a stationary member comprising 30 an angularly disposed downwardly projecting arm providing slide means for the end of an awning locking bar along its top surface and catch means for the engagement and retention of said awning locking bar 35 under said arm; a movable member of said bracket pivotally mounted on said stationary member and comprising a pair of parallel angularly disposed integral arms, each downwardly projecting at an angle approximately 45°; said arms positioned in parallel alignment and provided with a common slot extending throughout greater portion of their length; said slot adapted to accommodate said angularly disposed arm of said 40 stationary member; the upper and shorter of said arms adapted to provide cooperative means with said arm of said stationary member for stopping and retaining an awning locking bar; the lower and longer of said 45 parallel arms provided with a socket terminal for the accommodation and adjustable support of an awning frame member; said longer arm further provided with a longitudinal rib member pivotally supporting a 50 bridge and block member adapted to bridge and block the space between the lower ends of said parallel arms and provide slidable release means for the upward movement of an awning locking bar when in normal operation when raising the awning.

2. An awning bracket of the character described comprising in cooperative combination, a movable and a stationary bracket member; said movable member comprising 55 a pair of integral parallel angularly dis-

posed downwardly projecting arms of unequal length provided with a common slot throughout a greater part of their length; said stationary member provided with an angularly disposed downwardly projecting 70 arm adapted to be cooperatively accommodated through said slot of said movable integral arms; said stationary arm adapted to pivotally support said movable member and cooperate with said shorter of said parallel arms to provide slide means and stop means for guiding and stopping a horizontally disposed awning locking bar; said longer of 75 said parallel arms provided with a longitudinal rib along the upper edge thereof and a terminal socket at the lower end of the arm for the slidably adjustable support of an awning extension arm; a loosely pivoted bridge member supported at the lower end of said rib and when in normal operation 80 adapted to be moved pivotally into position for providing slidable and blocking bridge means for said awning locking bar over the lower and free end of said shorter movable arm, when releasing and raising the awning; 85 whereby when a window awning is mounted on a roller, the lower ends attached to a U-shaped frame member and provided with a central cross locking bar, the awning may be manually lowered from the inside or outside of the house; said locking bar slidably engaged by said bracket manually disengaged from said cooperating, stationary, and movable bracket members and slidably released from said engagement automatically 90 when it is desired to roll up the awning.

3. In combination with a window frame, a spring roller mounted adjacent the upper end of the frame, bracket supporting members hingedly mounted at their upper corners on the frame below the roller, a fabric strip having its lower end secured to the bight portion of the bracket and its upper end secured to the roller, bridge members pivoted to the outer ends of the lower arms of the bracket supporting members for movement about axes disposed transversely thereof, the bridge members being of a length to bridge and block the outer ends of the bracket supporting members and being disposed in alignment with the lower arms thereof when the bracket is in operative position, and a pull cord secured to the locking bar for unwinding the strip from the roller.

4. In a window awning of the character described having a roller mounted body member, a pivotally supported frame therefor and a cross rib lock bar; a bracket for the pivotal support of said frame member and the detachable engagement of said lock bar comprising a stationary member having a downward angularly disposed integral arm forming a slide rest and stop member and a moveable arm pivotally attached to said 120

- stationary member and comprising a pair of parallel arms of unequal length having a common longitudinal slot throughout a portion of their length for the pivotal accommodation of said stationary arm member; the upper and shorter of said integral moveable arms adapted to provide cooperative means with said stationary arm for stopping and retaining an awning locking bar; the lower and longer of said parallel arms provided with a socket terminal for the accommodation and adjustable support of an awning frame member, said longer arm further provided with a longitudinal rib member pivotally supporting a bridge and block member adapted to bridge and block the space between the lower ends of said parallel arms and provide slidable release means for the upward movement of an awning locking bar when in normal operation when raising an awning to which the bracket is attached.
5. An awning bracket comprising a stationary member having a downward angularly disposed integral arm forming a slide rest and stop member and a moveable
- arm pivotally attached to said stationary member and comprising a pair of parallel arms of unequal length having a common longitudinal slot throughout a portion of their length for the pivotal accommodation of said stationary arm member and the upper and shorter of said integral moveable arms adapted to provide cooperative means with said stationary arm for stopping and retaining an awning locking bar; the lower and longer of said parallel arms provided with a socket terminal for the accommodation and adjustable support of an awning frame member said longer arm further provided with a longitudinal rib member pivotally supporting a bridge and block member adapted to bridge and block the space between the lower ends of said parallel arms and provide slidable release means for the upward movement of an awning locking bar when in normal operation when raising an awning to which the bracket is attached.
